UNITED STATES PATENT OFFICE.

OTTO L. WEIMAR, OF PHILADELPHIA, PENNSYLVANIA.

SAFETY-ENVELOP.

1,077,773.

Specification of Letters Patent.

Patented Nov. 4, 1913.

Application filed June 13, 1913. Serial No. 773,481.

To all whom it may concern:

Be it known that I, OTTO L. WEIMAR, a citizen of the United States, residing at Philadelphia, in the county of Philadelphia and State of Pennsylvania, have invented 5 new and useful Improvements in Safety-Envelops, of which the following is a specification.

This invention relates to safety envelops; 10 and it has for its object the provision of a device of this character which will include a main retaining device on the back folds of the envelop and a locking member connected for rotation in one direction only with said 15 member and adapted to positively cause the sealing flap to be interposed between said second member and the adjacent flap of the envelop and thereby positively prevent the sealing flap from being opened without de- 20 tection.

With the above and other objects in view, the invention consists of certain novel features of construction, combination and arrangement of parts, as will be hereinafter 25 described and claimed.

In the accompanying drawings:—Figure 1 is a rear view of a portion of the envelop, showing the application of the invention thereto; Fig. 2 is a vertical section there- 30 through; Fig. 3 is a perspective view of one of the members of the fastener; Fig. 4 is a perspective view of the other member of the fastener; Fig. 5 is a perspective view of the spring disk; and Fig. 6 is a section, 35 showing a slightly modified form of the device.

The envelop 1 herein shown is provided with the usual overlapping back flaps 2 and a sealing flap 3, the latter in the present in- 40 stance being provided with an opening 4 therein for a purpose to be hereinafter explained. Arranged within the envelop and directly behind one of the flaps 2 is a disk 5, which has struck therefrom a plurality of 45 spurs 6 that are extended through the flaps 2 and then upset thereagainst, as at 7. The disk 5 is provided with an integral stud or lug 7, which is threaded at 8 and provided at its extremity with a transverse kerf 9. 50 The portions 10 and 11 of the lug are pro- vided with oppositely beveled and substan- tially cam surfaces 12, the lower ends of 55 which being disposed substantially on a line with the wall 13 of the kerf 9. The disk 5 described in the foregoing

forms one of the coöperating members of the fastener, and as illustrated particularly in Figs. 2 and 4, the other member 14 com- 60 prises a disk 15 incased in a shell 16, the latter having its marginal edge crimped, as 65 at 17, around the edge of the disk 15 and also around the edge of a metallic convex disk 18, the latter having a longitudinally curved spring 19 struck therefrom and ar- ranged with its medial portion aligned with the threaded opening 20 in said disk 15.

From this construction it is evident that the sealing flap 3 may be drawn over the open end of the envelop in the usual manner and the lug 7 of the disk 5 projected into the passage 4 of the sealing flap. The op- 70 positely beveled ends 12 of the portions 10 and 11 of the lug are then located beyond the sealing flap and the threaded portion of the lug disposed so that the companion 75 or coöperating member 14 of the device may be rotated on the lug and the spring 19 ad- vanced over the surfaces 12 and then finally locked in the kerf 9. The surfaces 12 per- 80 mit the member 14 to be rotated in one di- 85 rection only, and, as a consequence, when the sealing flap is in a secured position by rea- son of its confinement by the coöperating members of the fastener it cannot be drawn to a released position without being entirely destroyed.

In the modified form of the device shown in Fig. 6, the member 14^a is the equivalent of the member 14 in the preferred embodiment. The difference in this form of the 90 invention resides in the fact that the shell 16^a is swiveled at 21 to a metallic mounting 22 and the member 14^a directly carried by the sealing flap 3^a.

From the foregoing description, taken in 95 connection with the accompanying drawings, the construction and operation of the invention will be readily understood without requiring a more extended explanation.

Various changes in the form, proportion 100 and the minor details of construction may be resorted to without departing from the principle or sacrificing any of the advantages of this invention as claimed.

Having thus described my invention, 105 what I claim is:—

A fastener for envelops comprising a member secured to the envelop and provided with a threaded stud disposed in the closing path of the sealing flap and adapted to be 110

projected therethrough and provided with a kerf and operatively inclined surfaces at the sides of the kerf, and a threaded member adjustable on the stud and having a 5 yieldable portion operable over said oppositely inclined surfaces and adapted to be projected into the kerf so as to hold the second member against removal from the first member and to retain the sealing flap

in a confined condition between both members of the fastener.

In testimony whereof I affix my signature in presence of two witnesses.

OTTO L. WEIMAR.
